UNITED STATES PATENT OFFICE.

WILLIAM R. WILSON, OF YONKERS, NEW YORK, ASSIGNOR TO ALBERGER PUMP AND CONDENSER COMPANY, OF NEW YORK, N. Y., A CORPORATION OF NEW YORK.

COOLING-TOWER.

1,098,002.

Specification of Letters Patent.

Patented May 26, 1914.

Application filed October 1, 1912. Serial No. 723,286.

To all whom it may concern:

Be it known that I, WILLIAM R. WILSON, a citizen of the United States, residing at Yonkers, in the county of Westchester and 5 State of New York, have invented certain new and useful Improvements in Cooling-Towers, of which the following is a specification, reference being had therein to the accompanying drawing.

10 My present invention relates to certain new and useful improvements in cooling towers, and more particularly to that class of cooling towers in which air is circulated by means of one or more fans through the 15 spaces of an interior filling over which the water to be cooled is spread out so as to present an extended surface to the ascending air, or to a cooling tower in which a natural draft is set up in the stack by the ascending 20 heated air and vapor.

The object of the invention is to enable a cooling tower to be easily converted from a forced draft tower to a natural draft tower or from a natural draft tower to a forced 25 draft tower.

It consists essentially in means for easily and quickly providing the necessary opening at the bottom of the tower for the admission of air in order to enable the apparatus to 30 operate under a natural draft, and also for closing this opening in order to allow it to operate under a forced draft; and it also consists in numerous details and peculiarities in the construction, arrangement and 35 combination of parts substantially as will be hereinafter described and claimed.

In the accompanying drawing illustrating my invention; Figure 1 is a side elevation of my improved convertible cooling tower, a 40 portion thereof being broken away, and certain parts, especially those contiguous to the base, being shown in section. Fig. 2 is an enlarged sectional detail of the means for providing a water-seal in connection with 45 certain parts of the apparatus.

Similar characters of reference designate corresponding parts throughout the different figures of the drawing.

1 denotes an elevated stack of the ordinary construction, surmounting the tower proper 5. This is provided with a filling (not shown) over which the water to be cooled is spread out so as to present a large surface to the ascending air. The circulation 55 of the air through the tower may obviously be by a forced draft or a natural draft. When a forced draft is used a fan or fans, as at 2, are mounted on a horizontal shaft 3 placed below the filling in the lower portion of the tower casing 5. Said fan shaft will 60 be actuated by means of a motor or some other outside power. The water to be cooled falls through the tower from above and is caught below by the liquid basin or reservoir 4 from which it is removed. Said 65 reservoir 4 has an overflow 17 in order that a constant level of the water may be maintained. When the tower is to operate under a natural draft it is necessary to increase largely the air inlet at the bottom of 70 the tower, since the openings through the fan or fans at 2 are not sufficient to admit the necessary quantity of air.

The base 5 of the fixed portion of the tower casing on which the stack 1 is mounted, is itself mounted on piers or supports 6 and placed at a sufficient height above the water level carried in the basin 4, which basin forms a part of the foundation, to admit a free opening for the air. There may 75 be any suitable number of piers 6, sufficient, of course, to effectually support the tower.

7 indicates a sleeve, ring, or cylinder, which is vertically movable and is arranged in the lower portion of the casing 5 concentric therewith. This ring can be raised in order to permit of a free opening at the base of the tower for the free operation of the natural draft. When the ring 7 is thus raised it will be contained within the lower 80 portion of the casing 5, as indicated in Fig. 1. From this position it is susceptible of being lowered so that it will drop below the 85 bottom of the casing 5 into a position alongside of the supporting piers 6, and within the same, with its lower edge submerged below the level of the water in the basin 4, as shown by dotted lines in Fig. 1, thus 90 forming a water-seal. Near the top of the ring 7 it is provided on the outside with a 95 horizontal flange 8 which, when the ring is dropped into its lower position, is adapted to rest upon a corresponding horizontal flange 9 at the bottom and on the inside of 100 the fixed lower portion 5 of the tower casing. When the flange 8 is thus resting on the flange 9 it will be obvious, by referring to Fig. 2, that the upper edge of the ring 7 105 will form with the side of the casing 5, an annular channel 10 which will be filled by 110

the water falling through the tower and thus the joint at the top of the ring will be water-sealed. It will thus be observed that when the ring is in the position for the 5 tower to operate under a forced draft said ring 7 will be water-sealed at top and bottom, so that no air can enter the lower end of the casing 5, and the fan or fans will thus have an opportunity to do their best 10 work. But when the ring is raised into its top position the water-seals are both automatically broken and the ring is lifted entirely out of the way so that a large opening is afforded by the interior of the ring 7 15 through which the air coming between the piers 6 will ascend so that a natural draft can be effectively created by the ascending heated air and vapor.

The ring 7 is raised and lowered by means 20 of a vertical hydraulic cylinder 11 containing a piston 12 which is strongly secured centrally to the ring 7 by means of diagonal rods 13 or other similar suitable openwork construction that will enable the piston 12 25 to be rigidly attached to the ring 7 and yet will not obstruct the passage of the air through the ring 7 when the natural draft operation is in progress. The cylinder 11 is entered by a pipe 14 conveying fluid pressure 30 of any kind and controlled by a two-way valve 15 having an operating handle 16. The valve 15 allows pressure to enter the cylinder 11 through the pipe 14 and thus elevate the piston 12 and the ring 7. When 35 it is desired to lower the ring 7 the valve 15 will be operated by the handle 16 so as to cut off the pressure from the pipe 14 and allow such pressure as may be in said pipe and also in the cylinder 11 and under piston 40 12 to exhaust through a proper exhaust opening in said valve 15.

It follows from what I have already said that it is of the highest importance to prevent the passage of air beneath the tower 45 casing when the fans are in operation. To make this somewhat clearer, it may be said that the successful operation of a cooling tower depends upon bringing the air into contact with thin films of water, which films 50 are spread over the filling in the tower. Part of the water is evaporated in this manner and practically all of the cooling effect is produced by this evaporation. When the tower is operating under forced draft operation, if a free opening were left at the base 55 of the tower practically all of the air would pass out through this opening and it would not pass through the cooling tower filling and thus come in contact with the films of water for producing the cooling effect. The reason that under these circumstances the air would not pass through the filling is that the resistance through the filling would be greater than through the free opening at the 60 base of the tower; hence, the necessity of 65

closing the opening at the base of the tower when the latter is operating under forced draft conditions will be obvious.

Many changes in the construction and arrangement of parts may be made without exceeding the scope of my invention, and I reserve the liberty of making such variations in the detail of construction as may be necessary. I do not wish to be confined to the raising and lowering of the movable 75 ring by means of a fluid pressure cylinder, inasmuch as the same object may be accomplished by manifold other different kinds of mechanism. Also the means for supplying water pressure to a hydraulic cylinder 80 may vary within wide limits, since the pressure may be taken from any desired source, either the circulating system or otherwise. It will be found in the actual practice of my invention that many advantages are gained 85 where a change can be made quickly from a forced draft to a natural draft operation, inasmuch as the saving in power due to natural draft operation can be obtained whenever a light load or favorable temperature 90 and humidity conditions permit.

Having thus described my invention, what I claim as new and desire to secure by Letters Patent, is:—

1. In a cooling tower, the combination 95 with the tower and its base which receives the water falling through the tower, of a movable ring in the lower part of the tower adapted to be raised to provide an opening at the base of the tower for natural draft 100 operation.

2. The combination with a cooling tower, a water basin beneath, and a forced draft mechanism in the tower, of an extension ring at the base of the tower for connecting the 105 latter with the water basin during a forced draft operation and adapted to be lifted to provide a large opening at the base of the tower for natural draft operation.

3. The combination with a cooling tower, 110 a water basin beneath, and a forced draft mechanism in the tower, of a movable ring in the lower portion of the tower concentric therewith and adapted to be raised to provide an opening at the base of the tower for 115 natural draft operation, and means for raising or lowering said ring.

4. The combination with a cooling tower, a reservoir beneath said tower containing liquid, means for supporting said tower above the reservoir, a movable ring in the lower part of the tower, and a fluid pressure cylinder for raising and lowering the ring.

5. In a cooling tower, the combination of 125 a tower, a liquid reservoir beneath it, means for supporting the tower above the reservoir, a movable ring concentric with the tower and adapted to be raised and lowered so as to connect the tower with the liquid in the reservoir during a forced draft opera- 130

tion and to be lifted to leave an opening during the natural draft operation, and a hydraulic cylinder and piston, the latter connected to the ring, all arranged to operate in raising and lowering the ring, substantially as described.

6. The combination with a cooling tower, a liquid reservoir beneath it, piers supporting the tower above the reservoir, a movable ring in the lower part of the tower adapted to descend into the reservoir and to be raised into the tower above it, said ring having a flange engaging a flange on the bottom of the tower to provide a channel for a water-seal when the ring is lowered, and means for raising and lowering the ring.

7. The combination with a cooling tower and a liquid reservoir beneath it, of piers supporting the tower above the reservoir, and a concentric ring in the lower part of the reservoir adapted to be raised and lowered, said ring having a flange coöperating with the flange on the base of the tower

when the ring is lowered to form a water-seal, and a fluid pressure cylinder and piston, the latter connected centrally to the ring, all arranged to operate as specified.

8. The combination with a cooling tower, of a liquid reservoir beneath it, a movable ring in the lower part of the tower adapted to be raised or lowered, and means for water-sealing the ring at top and bottom when lowered during the natural draft operation.

9. The combination with a cooling tower, of a movable ring in the lower portion thereof, and means for raising or lowering said ring, together with means for water-sealing the ring at top and bottom when it is lowered.

In testimony whereof I affix my signature in the presence of two witnesses.

WILLIAM R. WILSON.
